INVENTOR

BY *Victor J. Evans*

ATTORNEY

UNITED STATES PATENT OFFICE.

ILE WINTER, OF STRINGTOWN, OKLAHOMA.

ENVELOPE.

1,411,547.

Specification of Letters Patent.

Patented Apr. 4, 1922.

Application filed September 11, 1920. Serial No. 409,542.

To all whom it may concern:

Be it known that I, Mrs. ILE WINTER, a citizen of the United States, residing at Stringtown, in the county of Atoka and 5 State of Oklahoma, have invented new and useful Improvements in Envelopes, of which the following is a specification.

The object of the present invention is the production of an envelope which cannot be 10 opened without detection.

The drawings illustrate the improvement. In the drawings:—

Figure 1 is a view of the envelope folded, and looking toward the back thereof.

15 Figure 2 is a sectional view approximately on the line 2—2 of Figure 1.

Figure 3 is a sectional view approximately on the line 3—3 of Figure 2.

Figure 4 is a perspective view showing 20 the arrangement of parts when the envelope is to receive the letter sheet therein.

Figure 5 is a view of the blank from which the envelope is formed.

My improved envelope includes a body 25 portion 1 which is scored to provide opposed flaps 2 and 3 and 8 and 9 respectively. The flap 2, has one of its edges provided with a substantially V-shaped tongue 5 that has on

30 its outer edge a coating of mucilaginous material 13. The flap 3, has a corner projection 7, and is formed with a V-shaped extension in the nature of a tongue 6 which is of a greater width and length than the tongue 5. Both the tongues 5 and 6 are foldable on the

35 respective flaps 2 and 3. The tongue 6, in a line with the edge of the flap 3 on which it is formed has a slot 4 therethrough of a size to receive the tongue 5. The tongue 6, on its outer face has its edges provided with a

40 mucilaginous substance 14. The flap 8 has its inner edges provided with a gummed or mucilaginous substance 8', and the said flap is centrally provided with a V-shaped incision providing the center thereof with a

45 tongue 10, and the said tongue on its inner face has its edges gummed. The flaps 8 and 9 are V-shaped in plan. The flap 9, however, is of a materially greater length than the flap 8, the outer portion thereof being

50 provided with a longitudinal score and the portion of the flap 9 outward of the score provides what I will term a tongue and which is designated by the numeral 11. The V-shaped tongue 11 has its edges gummed, 55 and the flap 9, for a determined length is gummed at its edges.

In assembling the envelope, the flap 2 is first bent over the body 1. The flap 3 is then bent over the flap 2. The tongue 5 is passed through the slot 4 in the flap 6 and is 60 adhesively connected to the outer face of the said flap. Thereafter the tongue 6 and the tongue 5 which is connected thereto, are bent inwardly against the inner face of the body 1, and the gummed surface 14 on the said 65 flap 6 is adhesively connected to the said body. The flap 8 is then bent over the flaps 2 and 3, and adhesively secured thereto. This leaves the envelope in a position to receive the letter sheet. When the sheet is arranged in the envelope the flap 9 is bent over the flaps 2, 3 and 8 and adhesively secured thereto. The tongue 11 is then inserted in the opening provided in the flap 8 by the arrangement of the tongue 10 at the center 75 thereof and is adhesively connected to the tongues 5 and 6. This leaves the flap 10 in a position to be brought over the flap 9 and adhesively secured thereto. The envelope is of a simple construction which may be 80 cheaply manufactured, and the manner in which the parts constituting the same are formed for interengagement and for adhesive connection positively prevents the surreptitious opening of the envelope, and in 85 fact the envelope cannot be opened even by an authorized person without tearing or mutilating the parts constituting the same so that such attempt will be rendered perfectly 90 obvious.

Having thus described the invention, what I claim, is:—

An envelope including a body having side and end flaps, each of the end flaps having one of their edges formed with a V-shaped 95 tongue, one of said tongues being of a greater length and width than the other, and both of the tongues being gummed, the wider tongue, at its center and in a line with the edge of the body having an opening therethrough for the passage of the tongue of the other end flap, when the flaps are folded over the body, said tongues, when in such position designed to be bent inwardly and the larger tongue adhesively connected to the 100 inner face of the body, both of the side flaps being V-shaped and gummed, one of the side flaps being provided with a V-shaped slit forming a tongue which has its edges 105 gummed, said last mentioned flap being designed to be folded over the end flaps and adhesively connected thereto, the other side 110

flap having a score line adjacent to its outer edge to provide the said outer edge with a tongue, said last mentioned flap designed to be folded over the first mentioned side flap 5 and the end flaps and to be adhesively connected thereto, the tongue on the last mentioned side flap adapted to be passed through the opening in the first mentioned side flap

provided by the tongue formed on the latter and to be adhesively connected to the larger 10 tongue of the end flap, and the tongue of the first mentioned side flap adapted to be folded over the last mentioned side flap and adhesively secured thereto.

In testimony whereof I affix my signature. 15
MRS. ILE WINTER.
